(57) **CLAIM**

The ornamental design for a carabiner organizer, as shown and described.

DESCRIPTION

FIG. 1 is a perspective view of a carabiner organizer according to the invention.

FIG. 2 is a front side view thereof.

FIG. 3 is a rear side view thereof.

FIG. 4 is a left side thereof.

FIG. 5 is a right side view thereof.

FIG. 6 is a top view thereof; and,

FIG. 7 is a bottom view thereof.

The broken lines in FIGS. 1 and 3-7 are for illustrative purposes only and form no part of the claimed design.
